VAPOR GENERATOR

Martin Frisch, New York, N. Y., assignor to
 Foster Wheeler Corporation, New York, N. Y.,
 a corporation of New York

Application April 29, 1949, Serial No. 90,483

5 Claims. (Cl. 122—459)

1

This invention relates to vapor generators and more particularly pertains to steam generators and to a method of and means for generating steam.

It has been determined that fouling of the blades of a turbine can be caused by very pure steam from the steam generator, that is, by steam containing a fraction of one part per million total solids as determined by the conductance method. Certain chemical constituents of boiler water, such as silica, the presence of which is not revealed by the conductance test, escapes from the boiler water into the steam in vapor form and, at high pressure, hydroxides, chlorides, sulphates, etc. are dissolved by the steam. In high pressure boilers particularly, silica is vaporized in the steam drum, entrained in said steam and passed in vapor form from the drum in admixture with the steam. The silica, because it is vaporized, is not removed by drying of the steam and passes to the turbine where it condenses on the turbine blades in the low pressure, low temperature stages thereof causing a marked reduction in the capacity of the turbine. The amount of silica vaporized in the boiler increases with the pressure, the saturation temperature, and the concentration of the boiler water from which the steam is released, and decreases as the pH increases. It is necessary, therefore, in order to maintain turbine capacity that only steam from which dissolved or vaporized solutes have been removed be passed to the turbine. Also, it is highly desirable that any scale formations caused by impurities from the feed water of a steam generator be confined substantially to tubes which are exposed only to relatively low temperature heating gases.

In accordance with the present invention, steam which is substantially free of dissolved or vaporized solutes is passed from a vapor generator while scale formations from impurities in the feed water of the steam generator are confined substantially to those tubes exposed only to relatively low temperature heating gases.

The invention has special application to high pressure, high temperature steam generators which are required to operate with feed water of high initial solid concentration, due to the necessity of using high percentages of make-up water. However, the invention is capable of application to steam generators generally.

In accordance with the present invention, pure steam, that is, steam free of dissolved or vaporized solutes, is produced and concentration of dissolved solids in the boiler water of the steam generator is controlled by arranging the heating

2

surface of the generator in two or more separate heat absorbing sections, each of which has its own independent circulation system. The feed water enters a primary high duty heat absorbing section which is continuously blown-down to a low duty secondary section. The secondary section comprises a plurality of tubular members with extended surface elements thereon which members are disposed in the path of flow of gases from the primary section and is subjected, therefore, to relatively low rates of heat absorption by convection.

A low boiler concentration is maintained in the highly heated furnace tubes of the primary section, while a much higher concentration is maintained in the moderately heated tubular members of the secondary section. The possibility of damage to the tubes in the primary or radiant heat absorbing section which operates at high heat transfer rates is minimized because in these tubes a low concentration is maintained, while in the secondary (convection) section which is subjected to low rates of heat transfer and low temperatures, high concentration can be tolerated. Also, since the concentration in the primary section where the major portion of the steam is generated is low in accordance with the present invention, the amount of silica or other solute vaporized is low. The steam released in the secondary section, which steam is made from the highly concentrated boiler water, will have a greater solute concentration but the steam generated in the secondary section is relatively small compared to the total boiler output. In accordance with the present invention, the mixture of steam and water formed in the secondary section is passed through a separator wherein steam is separated from said mixture, the separated steam thereafter being condensed and the condensate delivered to the primary section, while the steam-free water is returned to the secondary section. In this manner, entrained water is removed from the mixture of steam and water generated in the secondary section and the vaporized solute in the separated steam is condensed with said steam and thereby eliminated from the final steam product of the vapor generator of the present invention.

In the present invention, sub-cooling of the downcomers of the primary section is also prevented by washing the steam generated in the primary section in a portion of the feed water as the steam is treated in vapor and liquid separators thereby heating the feed water to saturation prior to the feed water entering the down-

3

comers and by condensing steam from the secondary section by direct heat exchange relationship with the remaining portion of the feed water.

The particular features and advantages which characterize the invention will be understood from the following description when considered in connection with the accompanying drawings forming a part thereof and in which:

Fig. 1 is a vertical sectional view illustrating more or less diagrammatically, the upper portion of a steam generator embodying the invention;

Fig. 2 is an enlarged vertical sectional view of the upper portion of Fig. 1;

Fig. 3 is a horizontal sectional view taken on the line 3—3 of Fig. 1;

Fig. 4 is an isometric view of a section of the steam and water drum illustrated in Fig. 1 on a larger scale;

Fig. 5 is a vertical sectional view, partly in elevation, taken on the line 5—5 of Fig. 1; and

Fig. 6 is an enlarged transverse sectional view taken on line 6—6 of Fig. 2.

Like characters of reference refer to the same or similar parts throughout the several views.

Referring to the drawings, Figs. 1 and 2, the steam generator of the present invention comprises a setting 10 having therein a combustion chamber 11 with a front wall 12 and a rear wall 13. The front wall 12 is inclined inwardly at the top thereof, as shown in Fig. 1, to form a roof 14 above which a steam and water drum 15 is positioned in substantial vertical alignment with rear wall 13. The walls of the combustion chamber 11 are lined with water wall tubes, the front wall 12 being lined with tubes 16 which connect at the upper end thereof with the bottom of drum 15, while the rear wall 13 is lined with water wall tubes 17 also connected at the upper end thereof with the bottom of steam drum 15. Side wall 18 is lined with riser tubes 19 connected at their upper end with a header 20. Header 20, in turn, communicates with drum 15 through tubes 21. A side wall, not shown, opposite wall 18 would also be lined with water wall tubes which would connect with an upper header similar to header 20 and which would also communicate with drum 15. The riser tubes 16, 17 and 19 would connect at their opposite ends with headers, not shown, which headers would receive water through a downcomer 21a. Downcomer 21a is in communication with drum 15 through a plurality of other downcomers 23 and receives water from drum 15 through said other downcomers.

Rear wall 13 extends upwardly a distance short of the drum 15 and roof 14 thereby providing a gas outlet 24 for the chamber 11 across which outlet the upper portion of water wall tubes 17 extend. Gas outlet 24 communicates with a downwardly inclined gas passage 25 which passage connects with a vertically extending passage 26. At the end thereof opposite that which communicates with passage 25, the passage 26 is in communication with a flue 27. As shown, a superheater comprising an inlet section 28, an intermediate section 29 and an outlet section 30 is disposed in the path of gases flowing through passage 25 from chamber 11 through gas outlet 24. The inlet section 28 receives steam from an inlet header 31 which inlet header communicates with drum 15 through steam conduits 32. Intermediate section 29 of the superheater is in communication with inlet portion 28 through a header 33 and with outlet portion 30 through a

4

header 34. Superheated steam is withdrawn from the superheater through an outlet header 35 which receives the steam from outlet section 30.

A secondary steam generating section 36 comprises a plurality of tubular members 37 having extended surface members thereon and positioned in passage 26 so that gases flowing through said passage pass in heat exchange relationship with said tubular members. The tubular members 37, as shown, extend transversely of passage 26 and are grouped in an upper group or portion 40 and a lower group or portion 41. The tubes of each portion are so connected with one another as to form a continuous flow path from the inlet header 38 to the outlet headers 39 of the secondary section. While the secondary section 36 is shown as comprising an upper portion 40 and a lower portion 41, the secondary section may be so arranged as to provide a single portion. The inlet header 38 receives boiler water blown-down from the primary section through a boiler water feed conduit 42 which is connected at one end thereof to the header and at the opposite end thereof to downcomer 21a.

Steam generated in the secondary steam generating section 36, which steam has entrained water therein, is passed to steam and water separating apparatus prior to the passage of said steam to drum 15. As shown more particularly in Figs. 2, 3 and 5, steam and water separating apparatus 43 comprises vertically extending elongated, substantially cylindrically-shaped headers 44 disposed adjacent one another in a horizontally extending row (Figs. 3 and 5) and to each of which is connected a plurality of riser tubes 45. Headers 44 are positioned at substantially the same level as drum 15 so that the water level WL in the drum and the water level WL' in the headers will be the same. Riser tubes 45 are connected at one end of a horizontally extending section 45' thereof with the upper portion of headers 44 above the water level WL' in the headers, said one end being in communication with the headers at one side thereof so that steam is introduced into said headers tangentially of the inner periphery thereof. The riser tubes 45 are connected at the opposite end thereof with the outlets 39 of secondary section 36. Each of the headers 44 has an outlet conduit 46 connected to the bottom thereof which conduit also communicates with inlet header 38 of secondary section 36. At the top thereof, headers 44 communicate with steam drum 15 through tubes 47. As shown in Fig. 1, the headers 44 are provided with a blow-down pipe 48 at the bottom thereof, of which blow-down pipes are connected to a horizontal header 49. Blowing-down of water through horizontal header 49 is controlled by a valve 50.

Steam, prior to passing from drum 15 into superheater inlet header 31 through conduits 32, is treated to eliminate moisture entrained therein which moisture carries dissolved chemicals, mechanically suspended fine particles of solid matters, vapor which condenses as solids and compounds dissolved in the steam. Such treatment is preferably accomplished by apparatus illustrated and described in applicant's co-pending United States patent application, Serial No. 90,484, filed concurrently herewith. As shown in Figs. 2 and 4, this apparatus comprises partitioning means so disposed in drum 15 as to form steam receiving chambers adjacent the inner periphery of the drum. The partitioning means comprises side plates 51 and 52 spaced

from the inner periphery of the drum at the opposite sides thereof and which extend longitudinally of said drum to points short of the opposite ends thereof in laterally spaced relationship to one another. The plates 51 and 52 each have an upper portion 53 and 54 respectively which extends inwardly of the drum and is secured to the longitudinally extending bars 55 and 56 respectively, the bars 55 and 56 being secured to the inner periphery of the drum. The partition plates 51 and 52 also have inwardly inclined bottom portions 57 and 58 inclined inwardly from the peripheral surface of the drum and in spaced relationship thereto, which bottom portions are similar to the top portions 53 and 54. A partition plate 59 of substantially the same length as plates 51 and 52 extends longitudinally of the drum in spaced relationship with the inner periphery thereof at the bottom, the opposite sides of plate 59 adjoining a longitudinal edge of plates 51 and 52.

Steam condensing chambers 60 and 61 are formed adjacent the upper part of plates 53 and 54 and between said plates and the inner periphery of drum 15 at opposite sides of the drum by metal partition members 62 and 63. The partition members 62 are secured at one end thereof to plate 53 below the inclined portion thereof and extend transversely of the drum to the inner periphery thereof and upwardly along said inner periphery to a point adjacent member 55 thereafter to project inwardly to be secured to the member 55. The partition member 63 is similar to the partition member 62 and is secured at one end thereof to partition 54 and at the opposite end to member 56. In this manner, steam condensing chambers 60 and 61 are formed, which chambers extend longitudinally of the drum adjacent opposite sides thereof so that the chambers 60 and 61 receive separated steam from headers 46 through tubes 47. These condensing chambers are open at the opposite ends thereof so that they communicate with the interior of the drum but are in fluid-tight relationship with steam receiving chambers 64 and 65, which are directly below condensing chambers 60 and 61 respectively. Steam receiving chambers 64 and 65 extend longitudinally of the drum at opposite sides thereof between partitions 51 and 52 respectively and the inner periphery of the drum respectively. Chambers 64 and 65 are in communication with passage 66 beneath bottom plate 59 and are closed at the opposite ends thereof by end plates 67 and 68 respectively and the passage 66 is closed at the opposite ends thereof by end plates 69 so that steam received within said chambers and passage from the primary section will pass into a central chamber 70 of the drum only through steam treating dryers 71 and 72. Central chamber 70 extends longitudinally of drum 15 in the central portion thereof, and is defined along the opposite longitudinal sides thereof by a row of steam and water separating boxes 78 and a row of steam and water separating boxes 79 respectively. The bottom of chamber 70, which is defined by partition plate 59, is in communication with downcomers 23 through outlet openings 73 in plate 59. Water from chamber 70 flows downwardly through openings 73 and fluid-tight passages 74 which conduct the feed water from chamber 70 through passage 66 and out of contact with steam flowing in said passage.

Feed water for the vapor generator of the present invention is fed to drum 15 through a plural-

ity of off-take conduits 75 and 76 extending from the opposite sides of a feed water pipe 77 disposed in central chamber 70 adjacent the bottom thereof and extending longitudinally of the chamber. 5 The off-take conduits 75 and 76 extend from the opposite sides respectively of pipe 77 and are laterally spaced from one another longitudinally of said pipe. Off-takes 75 extend transversely of the drum toward bottom portion 57 of partition 10 51, through said bottom portion into chamber 64 thence upwardly along partition 51 and into condensing chamber 60, thence along upper portion 53 to a point short of the top of said chamber. Off-takes 76 also extend transversely of the 15 drum 15 toward partition 52 thence through bottom portion 58 thereof, upwardly along partition 52 into condensing chamber 61 thereafter to extend along upper portion 54 to a point short of the top of chamber 61. 20 The plurality of separating boxes 78 and 79 are disposed in laterally abutting relationship with one another in rows which extend longitudinally of partition plates 51 and 52 respectively. As shown in Fig. 4, the separating boxes are substantially square in cross section and have a steam inlet slot 80 at one side thereof adjacent the bottom (Fig. 2), through which steam from chambers 64 and 65 enters the boxes 78 and 79 respectively. Feed water is injected into boxes 25 78 and 79 tangentially thereof through slots 80 by nozzles 81 and 82 (Fig. 6) which communicate with off-takes 75 and 76 respectively in order to accentuate the whirl within the boxes 78 and 79 and to effect mixing between the feed water and 30 boiler water. The feed water is divided among the plurality of boxes 78 and the plurality of boxes 79 so that each box receives an equal share of a predetermined fraction of the total feed water. Boxes 78 and 79 have steam outlets 83 and 84 35 respectively at the top thereof through which steam passes into spaces 85 and 86 respectively. The spaces 85 and 86 communicate with the upper portion of chamber 70 through dryers 71 and 72, which, as shown in Fig. 6, are of the chevron type. Each of these dryers (Figs. 4 and 6) comprises a plurality of laterally adjoining longitudinally extending rows each of which has a plurality of vertically extending horizontally spaced V-shaped plates which are positioned in 40 said row with the apex edge of one plate within the area bounded by the next adjacent plate in the row. The separating boxes 78 and 79 are open at the bottom thereof and in communication with the lower portion of chamber 70. 45 Feed water is projected from off-takes 75 and 76 into condensing chambers 60 and 61 respectively through outlet nozzles 87 and 88, said water impinging on hooked-shaped baffle plates 89 and 90. The baffle plates extend longitudinally of 50 chambers 60 and 61 and are so positioned as to direct the feed water downwardly into the chambers. Water from condensing chambers 60 and 61 flows into chamber 70 from the ends of said condensing chambers. 55 In operation, steam is generated in the primary high duty section of the steam generator of the present invention through the circulation of water from chamber 70 of drum 15 downwardly through openings 73 in partition 59, thence through passage 74 and through the plurality of 60 other downcomers 23 into downcomer 21a. Water from downcomer 21a passes into lower headers, not shown, thence into riser tubes 16, 17 and 18 in which tubes steam is generated by the 65 passage of gases of combustion in chamber 11 in 70 75

indirect heat exchange relationship with said tubes. The mixture of steam and water from these tubes enters steam chambers 64 and 65 through tubes 21, which tubes receive steam from headers 20.

Water and steam mixture entering chambers 64 and 65 is centrifuged and a portion of the steam is condensed in the separating boxes 78 and 79 respectively, the mixture entering said boxes through slots 80. Feed water from feed water pipes 77 also flows into boxes 78 and 79 through pipe 77, passing into boxes 78 through off-takes 75 and nozzles 81 positioned in slots 80 of boxes 78 and into boxes 79 through off-takes 76 and nozzles 82 positioned in slots 80 of boxes 79. The steam and water mixture from chamber 64 together with feed water from nozzles 81 flows into boxes 78 tangentially thereof, while steam and water mixture from chamber 65 likewise passes into boxes 79 thereby centrifuging or whirling the mixture and the feed water. The feed water is heated to saturation by being brought into direct heat exchange relationship with said steam and water mixture and a part of the steam is condensed. Centrifuging or whirling of the steam and water mixture together with the feed water also separates the water, the entrained moisture and any entrained substance of higher specific gravity than the steam from said steam. The separated steam, which is of lighter specific gravity than the feed water and entrained moisture or substance passes upwardly from the center of boxes 78 and 79 through steam outlets 83 and 84 respectively. The separated steam from boxes 78 enters space 85 and is directed by inwardly inclined portion 53 of partition 51 towards dryer 71 through which the steam passes and is dried by flowing through the space between the plurality of plates comprising the dryer. The separated water from boxes 78 flows downwardly along inwardly inclined portion 57 of partition 51 into central chamber 70 of drum 15 while the moisture separated from the steam in dryer 71 also flows downwardly into said chamber. The separated steam from boxes 79 passes upwardly therefrom through outlets 84 and is directed by inclined portion 54 of partition plate 52 into chevron dryer 72, while the separated water flows downwardly from boxes 79 into chamber 70. Since chambers 64 and 65 are in communication with one another through lower passage 66, the steam from one of said chambers may pass to the other chamber.

By treating the steam and water mixture and the feed water in boxes 78 and 79, as hereinabove described, dry steam only enters chamber 70 thereafter to flow into superheater inlet header 31 through steam conduits 32 and heated water flows into the lower portion of chamber 70 thereafter to pass into other downcomers 23 and thereafter into downcomer 21a.

The primary steam generating section is continuously blown-down to the header 38 of secondary steam generating section 36 through downcomer 21a and boiler water feed conduit 42. Water fed from header 38 passes into tubes 37 of upper portion 40 and tubes 37 of lower portion 41 of the secondary section thence into outlet headers 39. Steam is generated in tubes 37 by the passage of gases in indirect heat exchange relationship therewith which gases flow from chamber 11 through gas outlet 24 thence into passage 25 thereafter to enter vertically extending passage 26. The steam passes from outlet headers 39 into riser tubes 45 and passes there-

through into the steam and water separating headers 44.

In headers 44, steam and water is separated from the mixture thereof flowing into the headers from tubes 45 by the whirling or centrifuging of said mixture in the headers. The separated water passes downwardly in headers 44 and enters outlet conduit 46 through which it flows to inlet header 38 of the secondary section. The secondary section is blown-down through blow-down pipes 48 in headers 44 which blowing-down is controlled by valve 50. The rate of flow of boiler water to the secondary section through boiler water feed conduit 42 will be equal to the evaporation of water in the secondary section 36 plus the blow-down from the secondary section through blow-down pipe 48. Since the headers 44 and the drum 15 are positioned at the same level, the rate of flow of water through conduit 42 to the secondary section will be self-controlling and the water level WL' in the headers 44 will depend on the level WL in steam and water drum 15. When the level in the separator headers 44 drops, due to said evaporation and blow-down, additional water will pass from the main steam drum through downcomers 23, downcomer 21a and feed conduit 42 through the secondary section so that the levels WL and WL' will be maintained in equilibrium.

Separated steam from separating headers 44 flows upwardly in the headers to tubes 47 thereafter to flow to condensing chambers 60 and 61 in drum 15. The steam flowing into the condensing chambers is condensed by passing in direct heat exchange relationship with the remaining portion of the feed water flowing from off-takes 75 and 76, into the condensing chambers through nozzles on the end of said off-takes. The feed water from the off-take nozzles is directed downwardly in a sheet in front of the outlets of tubes 47 by means of baffles 90. Because of the high heat transfer rates through the direct contact of the feed water sheets and the steam from pipes 47, the steam will be completely condensed and the vaporized silica or other solute contained in the steam will go back into solution in the condensate. Condensate from chambers 60 and 61 drains downwardly into the feed water in chamber 70.

Although the invention has been disclosed as applied to the generation of steam, it is not limited thereto but is capable of application to the generation of vapors generally. From the foregoing, it will be perceived that by utilizing the apparatus of the present invention, pure steam that is, steam free of dissolved or vaporized solutes is produced and concentration of dissolved solids in the boiler water of a steam generator is controlled.

It will be understood that changes may be made in the form, location and relative arrangement of the several parts of the apparatus disclosed without departing from the principles of the invention. Accordingly, the invention is not to be limited excepting by the scope of the appended claims.

What is claimed is:

1. A steam generator comprising a setting having a combustion gas outlet, a plurality of steam generating sections in the setting each having a complete circulatory circuit, firing means, the firing means, the steam generating sections and gas outlet being so arranged in relationship to one another that gases of combustion flowing to the outlet pass in heat exchange relationship with one of said sections prior to flowing in heat

exchange relationship with another section, means for conducting water from said one section to said other section, separating means associated with said other section for receiving all of a mixture of steam and water generated in said other section and comprising a centrifugal separator in which the steam and water are separated from the mixture thereof by centrifuging, a steam offtake for said steam generator in communication with said one section only, blowdown means connected to a concentrated water containing portion of said other section, and means for condensing all of the steam separated in the centrifugal separator by passing it in heat exchange relationship with at least part of the feed water for the steam generator and adding the resulting condensate to the water of said one section by conducting it out of contact with the steam generated therein to a water containing portion thereof.

2. The steam generator of claim 1 wherein the separating means comprises a substantially cylindrically shaped chamber disposed with its longitudinal axis extending in a substantially vertical plane, the chamber being in communication with said other steam generating section so that a mixture of steam and water therefrom is introduced into the chamber tangentially thereof and steam and water are separated from the mixture thereof by centrifugal force.

3. A steam generator comprising a setting having a combustion gas outlet, a primary steam generating section having a complete circulatory circuit comprising an upper steam and water drum with downcomer and riser tubes in communication therewith, the downcomer tubes communicating with the drum to receive water therefrom and the riser tubes communicating with the drum to discharge steam thereinto, a secondary steam generating section having steam generating surface at a level lower than said drum and a complete circulatory circuit separate from the primary section, firing means, the firing means, steam generating sections and gas outlet being so arranged in relationship to one another that gases of combustion flowing to the outlet pass in heat exchange relationship with the primary section prior to flowing in heat exchange relationship with the secondary section, means for conducting water from the primary section to said secondary section, a steam offtake for said steam generator in communication with said primary section only, steam and water separating means comprising a housing having a substantially cylindrically-shaped chamber, the housing being

disposed so that the longitudinal axis of the chamber extends in a substantially vertical plane, the chamber being in communication with said other steam generating section to conduct separated water thereto, means for introducing all of a mixture of steam and water from the secondary section into the chamber tangentially thereof above the level of liquid therein thereby separating steam and water from the mixture thereof by centrifugal force, blowdown means connected to a concentrated water containing portion of said secondary section, and means for condensing all of the steam generated in said secondary section by passing it in heat exchange relation with at least part of the feed water for the steam generator and adding the resulting condensate to the water of said primary section by conducting it out of contact with the steam generated therein to a water containing portion thereof.

20 4. The steam generator of claim 3 wherein the secondary section comprises an economizer disposed in convection heat exchange relationship with said gases of combustion, and blow-down means for the steam generator communicates 25 with the separating means so that separated water is blown-down therefrom.

5. The steam generator of claim 3 wherein steam and water treating means is associated with the primary section, said steam treating 30 means being positioned in said drum and constructed and arranged to bring steam and feed water into heat exchange relationship with one another and thereafter separate the steam and water, the steam treating means also communicating with the steam offtake so that separated steam passes from the treating means thereto and with said drum so that separated water flows 35 thereinto.
